MECHANICAL MODULATOR

Morton Fuchs, New York, N. Y., assignor to Federal Telephone and Radio Corporation, New York, N. Y., a corporation of Delaware

Application November 6, 1943, Serial No. 509,252

10 Claims. (Cl. 179—171.5)

1

This invention relates to modulating systems and more particularly to modulating systems adapted for mechanical operation.

It is often desired to modulate energy transmitted with fixed tone frequencies, for example, in radio beacons. Such systems often take the form of rotating condensers or other mechanically moved impedance devices coupled across the line, or in series therewith.

It is often difficult readily to provide such mechanical modulators in a coaxial feed line.

It is an object of my invention to provide a modulator which may readily be used with a coaxial transmission line.

It is a further object of my invention to provide a modulator for use with a coaxial line, which may be applied without disturbing the inner conductor of said line.

It is a still further object of my invention to provide a modulator readily adapted for mechanical operation, associated with a coaxial feeding line.

According to the principles of my invention, I make use of a break or interruption in the outer or shield conductor of a coaxial transmission line effectively, to insert an impedance in series in the line. This effective impedance is made variable by a variable impedance means coupled effectively in parallel across the effective impedance. Thus, when the line is used to deliver power to a load, variation in the shunt impedance serves to modulate the power delivered to the load. The variable impedance may take the form of a condenser coupled across the break in the outer conductor, or between an open end of the conductor and ground or another neutral potential source.

A better understanding of my invention and the objects and features thereof may be had by reference to the description of particular embodiments thereof made with reference to the accompanying drawing, in which:

Fig. 1 is a diagrammatic illustration used in explaining the principles of my invention;

Fig. 2 is a set of curves used in connection with the diagram of Fig. 1;

Fig. 3 is an equivalent circuit diagram of the arrangement of Fig. 1;

Fig. 4 is a proposed structural arrangement in accordance with my invention;

Fig. 5 is a modified structural arrangement embodied in my invention; and

Fig. 6 is a still further structural arrangement embodying my invention.

In Fig. 1 is shown an arrangement incorporating the features of my invention in which a length

2

of coaxial line 10 is shown. This line comprises an outer or shield conductor 11 and a central conductor 12. A source 13 is coupled between conductor 11 and 12 at one end of section 10 and a load 14 is coupled between the central conductor 12 and ground 17. A further connection 15 is provided connecting the end of outer conductor 11 adjacent source 13 directly to ground 17. In accordance with this circuit arrangement, it is clear that effectively load 14 is connected to a point on the outside of outer conductor 11, as shown at 15. Thus, the open-ended conductor 11 interrupted at the point B with the load 14 coupled to a point on the outside thereof presents an impedance which is effectively in series with load 14. A variable impedance, shown as condenser 16 is connected also between the outer conductor and the neutral or ground potential source 17. This condenser is effectively in shunt with the impedance presented between outer conductor of the line and ground. Accordingly, by varying this impedance Z_{xc} a modulation of the energy supplied from 13 to 14 is obtained. A more complete analysis of the operation of the circuit, as shown in Fig. 1 is given below:

As shown in Fig. 1, the electrical length of coaxial line 10 is ϕ , the characteristic impedance of the line is Z_{0A} , the characteristic impedance of the outer conductor or shield is Z_{0B} . The effective impedance Z_{AB} which terminates line 10 is given by

$$Z_{AB} = \frac{V_{AB}}{i_1} \quad (1)$$

where V_{AB} is the voltage across AB and i_1 is the current flowing in the line 10.

Current i_1 flows within the shield and this current must come from the outside of the shield, as shown at 12. Now $i_1 - i_2 = 0$, so

$$i_1 = +i_2 \quad (2)$$

The impedance Z_{BC} between points B and C is equal to the external impedance of line 10, $jZ_{0B} \tan \phi$ in parallel with the impedance Z_{xc} of condenser 16.

$$Z_{BC} = \frac{jZ_{0B} X_c \tan \phi}{jZ_{0B} \tan \phi + X_c} \quad (3)$$

As X_c is varied Z_{BC} will follow the usual parallel resonance curve as shown in Fig. 2. The line 10 may be considered as terminated in Z_{0B} the load impedance in series with a variable Z_{BC} , as shown in the equivalent circuit of Fig. 3. Thus, by varying X_c , the voltage across the load 14 is modulated.

Turning to Fig. 4, a more practical constructive

arrangement of the circuit, as shown in Fig. 1, is illustrated. In this figure is shown a length of coaxial line 20 provided with an outer conductor 21 and an inner conductor 22. High frequency source 23 is connected between conductors 21 and 22. The outer conductor 21 is broken at 32 providing a gap which serves to introduce an impedance effectively in series with the load 24 connected between the center conductor and the outer conductor 21 of the line. A conductive support 25 serves to connect the end of line 20 adjacent source 23 to a source of ground or neutral potential 27. The portion of conductor 21 adjacent load 24 is also connected with ground or neutral potential, as shown at 33 and 34. The variable impedance is shown as a condenser 26 comprising stator plates 28 and 29 fixed respectively on the ground and the outer conductor 21 adjacent gap 32. It will be clear that stator 28 is effectively connected to the outer conductor 21 beyond gap 32. A rotor 30 is provided which may be driven at a constant speed by a motor 31. Rotation of rotor 30 tends continuously to vary the effective shunting impedance of this condenser between maximum and minimum values. If the portion of line 21 adjacent source 23 is made slightly less than a quarter wavelength at the operating frequency and the value of the condenser 30 is such that in its lowest capacitive position the outer conductor section is resonant, then the effective impedance in series with load 24 is infinite and no power flows thereto. As the condenser plate is rotated, the impedance reduces to some finite value so that one hundred percent modulation of the energy supplied to load 24 is obtained.

In the structural arrangement shown in Fig. 4, the rotor 30 is not exactly at ground potential since the rotor shaft and support has some electrical length. Actually, it may be preferable to construct the modulating arrangement of two mechanically balanced sections, such as shown in Fig. 5. In this figure, the line 40 is provided with an outer conductor 41 and inner conductor 42 coupled to a source 43. A gap 53 is provided and at equi-distant points spaced on opposite sides of gap 53 are provided supports 45 and 56 which serve to connect the two ends of line 40 to ground or other neutral potential source. The lengths of line between the gap and supporting points 45 and 56 are preferably made equal, and in the order of a quarter wavelength long. The variable impedance device comprises a condenser 46 having stator plates 48 and 49 fastened to outer conductor 41 on opposite sides of gap 53 and a rotor plate 50 rotatably supported between these plates 48 and 49 and driven at a constant speed by motor 51. It is clear that the two sections of line 41 between the gap 53 and points 45 and 53, respectively, provide two impedance elements effectively in series with the load. Rotor 40 is accordingly effectively in a neutral plane and therefore will assume the ground or neutral potential. For this reason, no special grounding of the rotor is required. The condenser tends effectively to shunt the impedance presented by the two line sections, and is variable between predetermined limits.

In Fig. 6 is shown a structural arrangement substantially similar to Fig. 5 in electrical effect. In this arrangement, however, the coaxial line 60 is bent in substantially a U-form with a gap 72 provided substantially at the apex of the U. Source 63 supplies energy to load 64 over the two conductors 61, 62 of the coaxial line. A common supporting and ground plate 65 is provided cutting the conductors transversely across the legs 75

of the U. On opposite sides of gap 72 are provided stator plates 68, 69 of condenser 66 and between these plates is supported the rotor 70 of the condenser. This rotor may be rotated at a desired constant speed by a suitable motor 71.

While I have illustrated variable condensers as the preferable forms of modulators used with the system of my invention, it should be clear that this is shown only by way of example. In connection with the mechanical modulating arrangement, however, condenser arrangements are generally preferred over inductors since considerably less impedance losses will occur in the capacitive than would occur in the inductive impedances.

It is clear, however, that the principles of my invention need not be confined to mechanical modulating systems of the type illustrated but any type of variable impedance may be provided connected between the conductor sections, as shown, or between a conductor section and a neutral ground point without departure from my invention. The specific examples and modifications thereof described in this specification are merely illustrations of my invention and should not be considered as limitations on the scope of my invention as set forth in the objects of the invention and the appended claims.

What is claimed is:

1. A modulating system for imparting a modulation to energy supplied from a source to a given load, comprising a section of coaxial transmission line, means for coupling said source between the inner and outer conductors of said transmission line at one end thereof, means for coupling said load between the inner conductor at the other end of said line and the outer conductor at said one end thereof, the outer conductor of said line being provided with a gap intermediate the ends thereof whereby the impedance with respect to ground of the outer surface of said outer line between its ends is effectively in series with said load, variable impedance means effectively bridged across said gap, and means for varying said variable impedance to modulate the energy supplied to said load.

2. A modulating system according to claim 1 wherein said section of coaxial transmission line from said source to said gap is made effectively a quarter of a wavelength long, and wherein said variable impedance is made variable between an effective short circuit and an effective open circuit condition, whereby one hundred percent modulation is substantially obtained.

3. A modulating system for imparting a modulation to energy supplied from a source to a given load, comprising a coaxial transmission line, the outer conductor of said line being provided with a gap, means for coupling said source between the inner and outer conductors of said line at one end thereof, means for connecting said outer conductor on the side of said gap toward said source to a neutral potential source, at a predetermined distance from said gap, a load connected to said line between the inner and outer conductors on the end remote from said source, a variable impedance means coupled between said outer conductors, and means for varying said variable impedance in accordance with modulating signals, to impart modulations to the energy supplied to said load.

4. A modulating system according to claim 3, further comprising means for connecting the end of said outer conductor immediately beyond said gap on the load end of said conductor to said neutral potential source.

5. A modulating system according to claim 3,

further comprising means for coupling said outer conductor on the side of said gap toward said load to said neutral potential source, at said predetermined distance from said gap.

6. A modulating system according to claim 3, wherein said variable impedance comprises a rotary variable condenser, and said means for varying said impedance comprises a drive means for rotating said condenser.

7. A modulating system comprising a coaxial line having an inner conductor and an outer conductor, the outer conductor being provided with a gap therein, means for connecting said outer conductor to a neutral potential source at equally spaced points on opposite sides of said gap, a high frequency energy source coupled between said inner and outer conductor at one end of the line, a load coupled between said inner and outer conductors at the opposite end of the line, and means for varying the impedance to the energy from said source as supplied to said load, comprising a variable condenser bridged across said gap.

8. A modulating system according to claim 7, wherein said coaxial line is formed in a substantially U shaped section, said gap being provided at the apex of said U.

9. A modulating system according to claim 7,

wherein said coaxial line is formed in a substantially U shaped section, said gap being provided at the apex of said U, said variable condenser comprising stator plates fastened to said outer conductor on opposite sides of said gap, and a rotor plate mounted for rotation between said stator plates, further comprising means for rotating said rotor plate.

5 10 15 10. A modulating system according to claim 7, wherein said variable condenser comprises stator plates fastened to said outer conductors on opposite sides of said gap, and a rotor plate mounted for rotation in spaced relation between said plates, further comprising means for rotating said rotor plate at a predetermined speed.
